UNITED STATES PATENT OFFICE.

MINER D. WOODLING, OF KANSAS CITY, MISSOURI.

RADIATOR-BRACKET.

1,393,874.

Specification of Letters Patent. Patented Oct. 18, 1921.

Application filed November 18, 1920. Serial No. 424,874.

To all whom it may concern:

Be it known that I, MINER D. WOODLING, a citizen of the United States, residing at Kansas City, in the county of Jackson and State of Missouri, have invented certain new and useful Improvements in Radiator-Brackets; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to a radiator bracket and particularly to a wall bracket whereby the radiator may be suspended above the floor so that access may be readily had beneath the radiator for the purpose of sweeping, cleaning, mopping, etc.

20 In carrying out the invention I have provided means whereby the radiator may be conveniently and expeditiously suspended from the side wall of a room or building and as conveniently removed, should the occasion demand.

25 The invention contemplates the provision of means whereby the bracket or suspending device for the radiator may be conveniently fastened to the side wall of the room and means is also provided whereby certain adjustments may be made to suit varying conditions encountered during the installation of the radiator.

30 In the drawings,

Figure 1 is a perspective view of the radiator and a bracket associated therewith.

Fig. 2 is a detail view of a stay rod hanger supported by the bracket securing bolt.

35 Fig. 3 is a top plan view of the radiator and the bracket in place.

Fig. 4 is a detail perspective view of the bracket hanger.

40 Fig. 5 is a sectional view through a slightly modified form of bracket, and

Fig. 6 is a detail view of a spacing sleeve.

45 In using the term "bracket" I contemplate the entire mechanism including the essential parts required to make an efficient anchor or suspension device for the radiator rather than to any particular element.

50 Referring now to the drawings by numbers of reference:

1 designates an expansion socket which 55 may be formed in the side wall 2, the socket

being interiorly threaded to receive the threads 3 of a headed bolt 4, upon which is mounted a hanger 5, through the opening 6 of which the bolt projects. The hanger 5 is provided with a right angular flange or shelf 60 7, provided with a central opening 8 through which a suspension rod 9 projects, the head 10 of which rests upon the flange or shelf 7 to support the rod 9. The suspension rod 9 carries a seating arm 11 at its lower end, 65 which is provided with a head 12 sleeved upon said rod and which rests upon the rod head 13, as clearly shown in Fig. 1. The rod 9 may, in effect, be an elongated bolt provided with the usual head 13 at one end 70 and a threaded opposite end to receive the head or nut 10. Such a construction is for the purpose of simplicity and to lessen the cost of manufacture because such bolts and rods are standard and need no special machinery for their construction.

75 The sleeved head 12 carries a laterally projecting, downwardly curved seating portion 14, upon which the radiator 15 may rest, the curvature of the seat 14 permitting the radiator to easily be seated and to provide for whatever expansion and contraction may occur in actual practice.

80 Interposed between the head 4 and the hanger 5 is an upstanding arm 16, indicated as a disk, having a rigid block 17 at one end thereof provided with a threaded opening to receive the threaded end 18 of a tie rod or stay bolt 19, which projects through the manifold and carries a clamping head 20 at 85 its outer end to engage between the manifolds in the form of a wedge and prevent the radiator from swinging outward. Inward swinging movement of the lower end 90 of the radiator is prevented by the laterally projecting stops or extensions 21 and 22 on the head 12. Therefore, when the parts are in the position shown in Fig. 1 the radiator will be securely held against accidental displacement and by reason of the fact that the parts constituting the bracket have certain relative movements, the engaged portions, both of the radiator and of the bracket members can readily find their natural seats so that fine adjustments will not be required 105 in order to efficiently set up the structure.

110 In Fig. 5 the construction of bracket is substantially like that shown in Fig. 1 except that instead of the exact construction of arm 11, a V-shaped arm 11' is provided.

for the purpose of supporting a radiator 23, the manifolds of which are polygonal in cross section. In all other essential respects, both forms of brackets are the same.

5. From the foregoing description it will be apparent that the radiator bracket may be efficiently set up by assembling the parts 5, 9, 11 and 16 and hanging the parts 16 and 5 upon the bolt 3, then introducing the bolt 10 into the socket 1. Then the radiator may be hung on the seats 14 of two adjacent brackets and the stay bolt 19, with its wedge-shaped block, screwed into the portion 17. In view of the fact that the part 16 has 15 swinging movement with respect to the bolt, there can be certain longitudinal play of the radiator in order to get it properly seated, the flexible connections between the members 16, 5 and 3 permitting a proper, 20 natural seat to be provided for all of the parts, this being an important feature of the invention.

Attention is called to the fact that the width of the flange 7 is approximately equal 25 to the thickness of the head 12 so that when the parts are arranged as shown in Fig. 1 with the head resting against the wall, the outer edge of the flange 7 and the faces of the stops 21 and 22 will be equal distances 30 from the wall.

When, however, the bracket is applied as shown in Fig. 5, with the head resting against the base board, the suspension rod will be inclined outwardly away from the 35 perpendicular, due to the fact that the base board will be interposed between the head and the wall. This will throw the radiator out from the wall a greater distance than according to the construction shown in Fig. 40 1 and, consequently, the top portion of the radiator will be moved away from the edge of the flange 7. In order to effect a stable construction, I may utilize a sleeve 19, shown in Fig. 6, which may be placed upon 45 the rod or bolt 19 to maintain the radiator in a vertical position irrespective of the fact that the rod 9 is inclined out of the perpendicular. Then if the rod 19 is screwed into the projection 17, the radiator may be 50 clamped between the head on said rod and sleeve to maintain the upper portion of the radiator in clamped, vertical alinement

with the bottom of the radiator held by the seat.

It will, therefore, be apparent that the 55 radiator bracket has considerable flexibility and is adapted to efficiently support radiators of different constructions to suspend them above the floor in an efficient and novel manner, the bracket being capable of being 60 expeditiously set up and taken down, should the occasion demand.

What I claim and desire to secure by Letters-Patent is:

1. A radiator bracket comprising a bolt, 65 a rod swingingly suspended from said bolt, a radiator seating bracket on said rod, a vertically swinging tie rod member on the bolt, and a radiator engaging tie rod eccentrically engaging said tie rod member. 70

2. A radiator bracket construction consisting of a laterally swinging, depending rod, a radiator seating bracket member on said rod, a rotatable member, the axis of which is in axial alinement with the pivot 75 of the swinging rod, and a tie rod connected to said last named bracket and having means for engagement with the radiator.

3. A radiator wall bracket construction comprising a laterally swinging, suspended 80 rod, a radiator seat carried by said rod, a member, the axis of which is in line with the pivot point of the rod, and a radiator engaging means connected to an eccentric portion of said member, 85

4. A radiator wall bracket construction comprising a wall-engaging bolt, a suspended rod carried by said bolt, a radiator seat on said rod, a rotatable member supported by the bolt and having an eccentrically disposed lug or projection, and a radiator supporting rod for lateral engagement with the lug or projection. 90

5. A radiator wall bracket construction comprising a pivot member, a depending 95 rod carried by said member, a radiator seat on said rod, a disk mounted on the pivot member and having an offset lug, and a laterally projecting radiator-engaging rod removably engaging said lug. 100

In testimony whereof I affix my signature.

MINER D. WOODLING.
